UNITED STATES PATENT OFFICE.

NICHOLAS HEYMAN, OF NEWARK, NEW JERSEY, ASSIGNOR TO HENRY KATZ & CO.,
OF NEW YORK, N. Y., A CORPORATION OF NEW YORK.

MECHANICAL TOY.

Application filed June 13, 1928. Serial No. 284,960.

This invention relates to an amusement device and toy for children and has reference especially to a mechanical toy designed to simulate traffic movements at a railroad terminal.

The principal object of my invention is to provide continuous paths over which trains or other moving objects are guided into and out of terminals and tunnels.

More particularly the purpose of this invention comprehends the provision of a railway terminal simulating toy wherein a plurality of trains or other moving figures are movable in parallel paths and in continuous lines, the power for operating the train lines being supplied by a spring motor of any well known construction and design.

A still further object of my invention is to provide a novel construction for the trains of cars used in the present toy. I accomplish these objects by means of the device illustratively exemplified in the accompanying drawing, fully described in the following specification and set forth in the appended claims.

In the drawings, Figure 1, is a side elevational view of my improved toy embodying the principles of this invention; Figure 2 is a bottom plan view of the same; and Figure 3 is a substantially longitudinal cross sectional view through one of the cars of a train, the path for the trains and the cable adapted to operate the cars.

Referring, in detail to the drawings, 10 denotes the shallow base or platform which comprises a skirt portion 11 depending from a rectangularly shaped sheet metal platform 12, which is decorated to represent the road bed of a railroad system. Disposed longitudinally of the platform 12 on opposite opposite sides of a line drawn longitudinally through the center, are continuous slots 13 which run parallel throughout substantially the entire length of the platform and terminate in semicircular portions at their opposite ends, as illustrated in Figure 2. At opposite ends of the platform 10 the latter carries transversely thereof inverted box shaped structures 14 which are decorated to represent a railway terminal 15 and rock formation 16 through which a tunnel 17 is disposed. The intermediate sections 18 inside each of the slots 13 are supported in position by transversely disposed braces 19

which are attached at their ends to the skirt 55 portions 11 of the base 10, as illustrated in Figure 2. An intermediate raised platform 20 is struck up from the longitudinal portion of the platform 12 and is intended to project to points short of the two structures 15 and 60 16. Suitable decorations and fixed figures arranged on the different portions of the platform will aid in giving the desired effect.

Operating in each continuous slot 13 is a 65 train of cars 21 comprising spaced rectangular car shaped units open at their under sides as illustrated in Figure 3. Each car has a top and upright walls, the side walls thereof having projecting portions adjacent opposite ends to simulate wheels 22, the lower edges of which rest on the platform 12 on opposite sides of the slot 13. The top wall of the car is provided with a centrally disposed longitudinal slot 22' through which 70 the prongs 23' of an upright cable grip 23 are projected, the grip 23 comprising a straight strip of metal projecting below the car 21 and into the continuous slot 13 over which the car is disposed. The cable grip 80 23 is supported adjacent the bottom of the car 21 between the wheels 22 by a transverse strip of metal bent at right angles from one of the side walls of the car.

The free lower end of the cable grip 23 85 is bent back upon itself to form a loop or eye 25 adapted to tightly embrace a portion of a continuous cable 26 operating directly beneath the slot 13 and through its entire length. The opposite ends of each cable 90 are disposed over grooved pulleys 27 which turn on shafts 28 depending from the platform 12 beneath the structure 15 and 16. The shaft 28^a of one of the pulleys 27 is rotatably mounted in the platform 12 and 95 extends upwardly into the interior of the structure 15. The shaft 28^a is used as a power shaft and receives its power from any suitable type of spring motor 29 indicated in the drawings by dotted lines. Beneath the 100 pulleys 27 on shaft 28^a is a second grooved pulley 30 over which one end of a continuous cable 31 is carried, the opposite end of the latter being arranged over a similar pulley 32 which is integral with the pulley 27 105 of the other cable 26 at the same end of the device. It will be clear that rotary movement of the shaft 28^a will be imparted to the

two cables 26 which during movement thereof carry with them the cars of each train 21. A brake or stop arrangement is provided in the device and comprises a rod 33 rotatably mounted between the end portion of the skirt 11 and adjacent cross brace of rod 19, the mid portion of the rod 33 being offset to form a crank 34 which is adjustable into a position against the surface of the pulley 32.

In operation, the motor is wound up and the brake rod 33 is released, whereupon the pulleys 27 rotate and cause the cables 26 to travel beneath their respective slots 13. The cars 21 through their cable grips 23 are transported along the slots 13 in a continuous path. According to the arrangement of the cable 31, shown in Figure 2, the two car cables 26 will travel in the same directions, but if it is desired to have them travel in opposite directions the cable 31 may be crossed.

Having now described my invention what I claim and desire to secure by Letters Patent is:

1. In an amusement device, a platform having a plurality of continuous slots forming paths which run parallel to each other adjacent opposite sides of the platform, a continuous cable to travel beneath each slot, cable grips clamped to the cables and projecting uprightly through the slots to carry objects along the slots, and means for operating one cable from the movement of the other.

2. An amusement device, as claimed in claim 1, in which said means comprises pulleys mounted on the platform and supporting the cables in line beneath the slots, a second pulley for one of the pulleys of each cable, and a cable operating over each second pulley to operate one of the first named cables from the movement of the other.

3. An amusement device, as claimed in claim 1, in which the platform comprises a flat rectangular portion in which the slots are disposed, a skirt depending marginally about the flat portion, pulleys arranged on the under face of the flat portion to receive the cables and operate them beneath and along the slots and in which said means for operating one cable from the movement of the other comprises, a second pulley for one of the pulleys of each cable, a cable operating over said second pulleys, box-like structures at opposite ends of the flat portion arranged over the portions of the slots and cables overlying the pulleys, and a train of cars for each cable comprising box-like structures arranged in inverted positions over the slots, each car being mounted on one of the cable grips operating in the slots.

In testimony whereof I affix my signature.

NICHOLAS HEYMAN.
